CLAIM

The ornamental design for a vehicle calibration device as shown and described.

DESCRIPTION

FIG. 1 is a front elevational view of a vehicle calibration device showing our new design;

FIG. 2 is a back elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a first perspective view thereof.

The broken lines shown are included for the purpose of illustrating portions of the vehicle calibration device that form no part of the claim.
